RAIL BOND TERMINAL

Ernest J. Sabol, Pittsburgh, Pa., assignor, by
mesne assignments, to Asbury G. Wilson, John
Richard Wilson, and Theodore F. Wilson,
Wilkinsburg, Pa., copartners trading as Hanlon
& Wilson Company

Application March 16, 1942, Serial No. 434,883

4 Claims. (Cl. 287—20.3)

This invention relates generally to rail bonds and more particularly to the terminals of such rail bonds. As is well known, rail bonds are used for the purpose of connecting the ends of adjacent railway rails in order to form a part of the electric current of a signaling system. In the type of rail bond terminal to which the present invention relates, the terminal is of the kind which has an expandible stud adapted to be received in a cavity in the rail. A soft metal, for example copper, is placed in the bore of the stud and a pin is inserted into the bore and driven into or against the soft copper, causing it to expand and thereby expand the stud of the terminal into contact with the rail.

In the terminals of the type herein referred to, considerable difficulty has been encountered in providing a terminal in which the pin is so tightly locked in the terminal as not to become loosened by vibrations caused by the train running on the rail to which the rail bond is connected. The terminal is subjected in use to extreme vibrations which in time tend to cause the pin to become loose from the terminal and the pin lost making the bond unfit for reuse without the pin, in case the bond is to be removed for any of the following reasons: track moving, building up of track ends or relocation of old steel to locations where traffic demands are not so great. This practice is not uncommon with many of the railroads. One of the original requisites for an all around rail head bond was that the bond be of such design that it can be removed and reinstated.

Another reason for locking the pin within the terminal head is to reduce to a minimum the possibility of the pins vibrating loose and being lost in transit when shipped. In accordance with the present invention, a tapered pin is locked in a bore in the terminal head. In assembling the tapered pin in the terminal head, the terminal is provided with a cylindrical bore having a diameter sufficiently large so as to receive the large end of the tapered pin. A soft material, such for example as copper, is placed in the bottom of the bore and thereafter the large end of the pin is inserted in the bore. The outer end of the head of the terminal is pressed inwardly against the tapered pin so as to firmly lock it in the head by upsetting the outer end of the head adjacent the bore.

In the accompanying drawing, which illustrates a preferred embodiment of the rail bond terminal and a preferred method of making and applying the same to a railway rail:

Fig. 1 is a horizontal section taken through a portion of a railway rail and a portion of a rail bond;

5 Figs. 2 and 3 are vertical sections through a terminal and associated mechanism for upsetting the head of the terminal against the driving pin;

In Figs. 1, 2 and 3, the driving pin is shown in elevation; and

Fig. 4 is a front elevation of the driving pin.

Fig. 1 shows the terminal, which is indicated generally by the reference numeral 2 locked in place in the railway rail 3. The rail bond comprises a conductor 4 such as a plurality of wires, the end 5 of the conductor being encased in a sleeve 6, both of which are made integral with the head 7 of the terminal by electric welding the conductor end and sleeve end to the terminal head. The terminal comprises the head 7 and an expandible stud 8 which fits into a recess or cavity 9 in the rail. A bore 10 extends through the head 7 and through a substantial portion of the length of the stud 8, the lower end of the bore being closed by the end wall 11 of the stud. A soft metal, for example, copper, or other material capable of flowing under pressure, designated by the reference numeral 12, is located in the inner end of the bore and is expanded by driving in the tapered pin 13 to the position shown in Fig. 1. The inner end of the pin 13 is provided with a reduced portion 14 which in the embodiment shown is of conical shape and acts as an expander for penetrating the copper 12. When the pin is driven into the position shown in Fig. 1, it expands the copper and also expands the stud 8 into tight engagement with the wall of the rail cavity.

It will be noted that the pin 13 has a cylindrical portion 13a forming the lower end of the pin body. This cylindrical portion guides the pin, 40 so that it does not gouge the bore of the terminal head and cause an angle between the axis of the bore and the axis of the pin. It has been determined by actual research that if the pin is not maintained in strict alignment with the bore, improper installation will result.

45 A method of making a rail bond terminal of the type shown in Fig. 1 is illustrated in Figs. 2 and 3. The stud 8 of the terminal is received in an opening 18 of a support or anvil 19, the shoulder 20 between the head 7 and the stud 8 resting on the upper surface 21 of the support. The terminal has a bore 22 which extends throughout the length of the head and throughout a substantial portion of the stud. This bore 50 is substantially cylindrical in shape and of a di-

ameter slightly larger than the diameter of the cylindrical portion 13a of the tapered pin. A quantity 12 of copper or other soft material is first placed in the bore and thereafter the tapered pin is placed in the bore in the position shown in Fig. 2. A pocket 23 may be preformed in the copper before the copper is placed in the bore in order to receive the cone-shaped expander section 14, which extends from the inner end of the body portion of the tapered pin. The tapered pin is so located in the bore that a space 24 is provided between the top surface of the copper and the shoulder 25 of the tapered pin. An upsetting die or plunger 26 is then brought into the position shown in Fig. 3. The die has a centrally disposed hole 27 which receives the upper end of the tapered pin. However, this hole 27 is of sufficient length so that even when the die is brought down in order to upset the head 1 the bottom 28 of the hole is spaced from the outer end 29 of the tapered pin. The bottom of the die 26 is formed of two surfaces 30 and 31 disposed at an angle to each other, in order to form the annular ridge 32. When the die 26 is pressed down into contact with the head 1 of the terminal, the ridge 32 penetrates the head and forms the annular V-shaped groove 33 adjacent the bore as shown in Fig. 3. As the die 26 is pressed against the head 1, the annular ridge 32 penetrates the head and due to the sloping surface 30 the die upsets the head, forcing that portion adjacent the bore into engagement with the tapered pin. This locks the tapered pin within the head of the terminal, so that it cannot become loosened. It will be noted that even after the head of the terminal has been upset against the tapered pin, as shown in Fig. 3, there still is a space 24 between the body portion of the tapered pin and the upper surface of the copper 12.

In making the connection of the terminal to the rail, the stud 3 of the terminal is placed in a recess or cavity 9 in the rail, as shown in Fig. 1, and the tapered pin is given a few blows by a hammer so as to drive the conical expander section 14 of the pin into the copper, thereby causing the copper to expand and also expanding the stud into tight engagement with the rail.

It is to be noted that these terminals are of small size, usually only about $\frac{1}{2}$ the size shown in the drawings, and that accordingly the taper of the pin is only very slight. Also the movement of the pin in the bore in securing the terminal to the rail is very slight. After the terminal has been secured to the rail by driving the tapered pin from the position shown in Fig. 3 to that shown in Fig. 1, any looseness of the pin in the bore may be overcome by again upsetting the head of the terminal to force it into tight engagement with the pin in a manner similar to that shown in Fig. 3. This simply involves placing an upsetting tool 26 over the terminal head and pin and striking the upsetting tool to force the head against the pin. This second upsetting operation may not be necessary in all cases because the taper of the pin and the movement of the pin in expanding the stud 3 are very small. Even without the second upsetting operation, the pin is retained in the bore because of its tapered construction.

It will be seen from the above description that I have provided a rail bond terminal in which a

tapered pin is employed as a driving pin for expanding the stud portion of the terminal into tight engagement with the rail. This pin and the bore in which it is received taper outwardly from the rail, so that the pin is always securely locked in the terminal.

The invention is not limited to the preferred embodiment, which has been given merely for illustrative purposes, but may be otherwise embodied or practiced within the scope of the following claims.

I claim:

1. A rail bond terminal comprising a head, an expansible stud adapted to be received in a rail cavity, a bore extending through the head and through a substantial portion of the length of the stud, one end of the bore being closed by the end wall of the stud, a relatively soft material in the bore of the stud, the bore in the head tapering toward its outer end, and a pin of relatively hard material in the bore, said pin tapering toward the outer end of the bore and adapted to be driven against said relatively soft material to expand the stud into tight engagement with the rail.

2. A rail bond terminal comprising a head, an expansible stud adapted to be received in a rail cavity, a bore extending through the head and through a substantial portion of the length of the stud, one end of the bore being closed by the end wall of the stud, a relatively soft metal in the bore of the stud, the bore in the head tapering toward its outer end, and a pin of relatively hard metal in the bore, said pin tapering toward the outer end of the bore and having a reduced end expander section at its inner end adapted to be driven into said relatively soft metal to expand the stud into tight engagement with the rail.

3. A rail bond terminal comprising a head, an expansible stud adapted to be received in a rail cavity, a bore extending through the head and through a substantial portion of the length of the stud, one end of the bore being closed by the end wall of the stud, a relatively soft metal in the bore of the stud, the bore in the head tapering toward its outer end, and a pin of relatively hard metal in the bore, said pin tapering toward the outer end of the bore and having a reduced end expander section at its inner end adapted to be driven into said relatively soft metal to expand the stud into tight engagement with the rail, the head being upset adjacent the open end of the bore to force the head into engagement with the tapered pin.

4. A rail bond terminal comprising a head, an expansible stud adapted to be received in a rail cavity, a bore extending through the head and through a substantial portion of the length of the stud, one end of the bore being closed by the end wall of the stud, a relatively soft material in the bore of the stud, the bore in the head tapering toward its outer end, and a pin of relatively hard material in the bore, said pin having a cylindrical portion forming the lower end of the pin body and acting to guide the pin in the bore of the terminal head, said pin tapering toward the outer end of the bore and adapted to be driven against said relatively soft material to expand the stud into tight engagement with the rail.
